HEDDLE FRAME

John Jacob Kaufmann, Elkins Park, Pa., assignor
to Steel Heddle Manufacturing Company, Phil-
adelphie, Pa., a corporation of Pennsylvania

Application September 13, 1934, Serial No. 743,793

10 Claims. (Cl. 139—92)

My invention relates to heddle frames for looms, and more particularly to improved means, in a heddle frame of the usual type, for supporting the heddle bars intermediate their ends and for positively locking the heddle bars in fixed position.

The principal object of my present invention is to provide, in a heddle frame, improved means for supporting the heddle bars intermediate their ends and for locking said bars against undesirable motion or displacement, yet permitting the bars to be quickly and conveniently mounted in the frame and removed therefrom when desired.

My present invention contemplates an improved form of heddle bar supporting device which may be readily adjusted with respect to the top and bottom rails of the frame, so that the heddle supporting bars will be properly positioned and the heddles will not bind thereon.

My present invention further contemplates an improved form of supporting device in which a positive locking of the heddle bars with respect to the frame is provided, whereby wear of the contacting surfaces of the bars and the support will be reduced to a minimum.

My present invention further contemplates certain improved details of construction, whereby the device will be rendered more durable and efficient.

Other objects of my invention will appear from the specification and claims.

The nature and characteristic features of my invention will be more readily understood from the following description, taken in connection with the accompanying drawing forming part hereof, in which:

Figure 1 is an elevational view of a heddle frame provided with heddle bar supporting devices embodying the main features of my present invention;

Fig. 2 is an enlarged fragmentary side elevation, partly in section, of a portion of the heddle frame structure, with one of the supporting devices embodying the main features of my present invention shown in connection therewith, the parts being shown in the positions assumed prior to the effecting of the positive locking of the heddle supporting bars;

Fig. 3 is a view similar to Fig. 2, the parts being shown in the positions assumed for positive locking of the heddle supporting bars;

Fig. 4 is an enlarged section taken approximately on the line 4—4 of Fig. 2, illustrating one of the supporting devices in positive locked position;

Fig. 5 is a perspective view of a bolt member forming a component part of the device, the other parts being removed therefrom;

Fig. 6 is an enlarged vertical central section of one of the locking elements forming part of the device; and

Fig. 7 is an elevation illustrating a preferred form of telescoping spring employed.

It will, of course, be understood that the description and drawing herein contained are illustrative merely, and that various modifications and changes may be made in the structure disclosed without departing from the spirit of my invention.

Referring to the drawing, the heddle frame there shown comprises top and bottom rails 10, connected at their ends by means of the side members 11. Extending from end to end of the heddle frame, and near the top and bottom rails thereof, are the heddle bars 12, upon which the heddles 13 are mounted in the customary manner.

The heddle bar supporting devices 14 comprising the present invention are mounted at suitable locations on the inner edges of the top and bottom rails 10. Each of these devices 14, as shown in the drawing, includes a bolt member 15 having a shank, the end of which is threaded at 16 in a manner similar to that of an ordinary wood screw, with the exception that the same is not tapered over as large a portion of its length. The bolt member 15 is also provided with a second threaded portion 17, for purposes to be hereinafter set forth. The threads on this part are preferably of the form ordinarily used for machine screws.

A head portion 18 is also provided on the bolt member 15, and is preferably made by flattening and spreading the material of the rod from which the bolt member is formed. The flattened head member 18 is provided with one or more shoulders 19, near one end thereof. In the drawing two such shoulders are shown.

On each side of the flattened head portion 18 of the bolt member 15 there is mounted a plate 20, which may be secured to said bolt member by rivets 21 or any other suitable fastening means. The plates 20 are provided with recesses 22, these recesses being of greater width than the width of the heddle supporting bars which are adapted to be mounted therein. The surface of the plates 20 on which the heddle supporting bars 12 rest are formed as continuations of the corresponding surfaces of the head portion 18 of the bolt member 15, and also of the shoulders 19 thereon.

A slideable clamping member 23 is mounted on

the bolt member 15, and is provided with vertically extending legs 24 which straddle the head portion 18 of the bolt member 15. The leg portions 24 of the slideable clamping member 23 are 5 guided between the plates 20 which are secured to the head portion 18 of the bolt member 15. The lower end of each of the leg portions 24 is provided with a lip 25, which is adapted to extend down over the outside of the heddle supporting 10 bar 12.

A positive locking member 26 is also mounted on the threaded portion 17 of the shank of the bolt member 15. The member 26 may take the form of a nut with an internally threaded portion 27 for engagement with the threaded portion 17 of the shank of the bolt 15. The member 26 may be knurled, roughened, or otherwise shaped or deformed on the circumferential face thereof, to provide a suitable gripping surface. 15 The face of the member 26 is preferably recessed, as at 28.

A conical telescoping coil spring 29 is mounted on the shank of the bolt member 15, and is interposed between the positive locking member 26 25 and the slideable clamping member 23. One end of the spring 29 bears against the horizontal portion 30 of the slideable clamping member 23, and the other end thereof is received within the recess 28. It will be noted that the depth of the 30 recess 28 is greater than the thickness of the wire employed in making the spring 29, so that upon compression the spring will be completely encompassed within the space defined by the rim 31 of the recess 28 and the horizontal portion 30 of the 35 slideable clamping member 23. The rim portion 31 of the member 26 may thus be brought to bear directly upon the slideable clamping member 23.

It will be noted that with the positive locking member 26 in the position shown in Fig. 2, the 40 slideable clamping member 23 may be moved against the force of the coil spring 29 to permit the insertion of a heddle bar 12. The action of the spring 29 on the slideable member 23, with its lip 25 in engagement with the heddle bar 12, then 45 securely holds said bar against the shoulder 19 of the shank of the bolt 15, and against the shoulders provided by the recesses 22 of the plates 20. The positive locking member 26 is then turned, and the spring 29 is compressed until the rim 31 is 50 in firm contact with the horizontal face 30 of the slideable clamping member 23. This provides a positive lock of the heddle bar with respect to the support, and vibration or shocks will not have any appreciable effect in loosening the locking means. 55 Movement of the bar with respect to the support, with undesirable wear, is thus prevented.

The removal of the bar may be readily effected by turning the positive locking member 26 in the opposite direction from that required for locking.

60 While the invention has been described for a double heddle bar support, it will of course be understood that it may be applied equally well to a single heddle bar support, in which case the slideable clamping member 23 is provided with but 65 one lip 25 and the support has only one shoulder 19 for receiving the heddle bar.

I claim:

70 1. In a loom heddle frame, a heddle bar upon which the heddles are mounted, a support for the heddle bar intermediate its ends, said support having a shoulder for receiving the heddle bar, a member slidably mounted on the support for engagement with the heddle bar thereby to hold it in position on the support, a telescoping spring 75 mounted on said support and having a portion

bearing against the member to urge it toward the heddle bar, and a locking nut threaded on said support and provided with a recess in which said spring bears.

2. In a loom heddle frame, a heddle bar upon 5 which the heddles are mounted, a support for the heddle bar intermediate its ends, said support having a shoulder for receiving the heddle bar, and means for holding said heddle bar in position on said support, said means including a member 10 slidably mounted on the support for engagement with the heddle bar, a telescoping spring mounted on said support and having a portion bearing against said member, a positive locking member threaded on said support and bearing against a portion of said spring, said locking member being adapted to be advanced to compress said spring and hold said slidably mounted member in positive locked position.

15 3. In a loom heddle frame, a heddle bar upon which the heddles are mounted, a support for the heddle bar intermediate its ends, said support having a shoulder for receiving the heddle bar, and means for holding said heddle bar in position on said support, said means including a member 20 slidably mounted on the support and adapted to engage the heddle bar, a coil spring surrounding said support and having a portion bearing against the member to urge it toward the heddle bar, and a locking nut threaded on said support 25 and adapted to be advanced thereon to compress said spring and urge said member to heddle bar locking position.

25 4. In a loom heddle frame, a heddle bar upon which the heddles are mounted, a support for the heddle bar intermediate its ends, said support having a shoulder for receiving the heddle bar, a member 30 slidably mounted on the support and adapted to engage the heddle bar thereby to hold it in position on the support, a locking nut threaded 35 on said support and provided with a recess, and a spring surrounding said support and bearing on said member and in the recess of said nut, said nut being adapted to be advanced on said support 40 to urge said member to heddle bar locking position and to bear against said member.

45 5. In a loom heddle frame, a heddle bar upon which the heddles are mounted, a support for the heddle bar intermediate its ends, said support having a shoulder for receiving the heddle bar, and means for positively locking said heddle bar against said shoulder including a member 50 slidably mounted on the support for engagement with the heddle bar, a locking member threaded on said support and adapted to be advanced thereon to 55 hold said member in heddle bar locking position, one of said members being provided with a recess, and a spring adapted to be compressed into said recess.

60 6. In a loom heddle frame, a heddle bar upon which the heddles are mounted, a support for the heddle bar intermediate its ends, said support having a shoulder for receiving the heddle bar, and means for positively locking said heddle bar against said shoulder including a member 65 slidably mounted on the support for engagement with the heddle bar, a locking member threaded on said support and adapted to be advanced thereon to contact said slidably mounted member, said locking member being provided with a recess, 70 and a spring adapted to be telescoped into said recess.

75 7. In a loom heddle frame, a heddle bar upon which the heddles are mounted, a support for the heddle bar intermediate its ends, said support

having a shoulder for receiving the heddle bar, and means for holding said heddle bar in position on said support, said means including a member mounted on the support for engagement with the 5 heddle bar, a spring mounted on said support and having a portion bearing against said member to urge it toward the heddle bar, and a locking member adjustably mounted for longitudinal movement on said support to locking position, said 10 locking member being provided with a recess in which said spring is received.

8. In a loom heddle frame, a heddle bar upon which the heddles are mounted, a support for the heddle bar intermediate its ends, said support 15 having a shoulder for receiving the heddle bar, and means for holding said heddle bar in position on said support, said means including a member mounted on the support for engagement with the heddle bar, a spring mounted on said support and 20 having a portion bearing against said member to urge it toward the heddle bar, and a locking member adjustably mounted for longitudinal movement on said support to locking position, one of said members being provided with a recess in 25 which said spring is received.

9. In a loom heddle frame, a heddle bar upon which the heddles are mounted, a support for the

5 heddle bar intermediate its ends, said support having a shoulder for receiving the heddle bar, and means for holding said heddle bar in position on said support, said means including a member mounted on the support for engagement with the heddle bar, a spring mounted on said support and having a portion bearing against said member to urge it toward the heddle bar, and an adjustable member mounted on said support for movement 10 to heddle bar locking position, said adjustable member being provided with a recess in which 15 said spring bears.

10. In a loom heddle frame, a heddle bar upon which the heddles are mounted, a support for the heddle bar intermediate its ends, said support 15 having a shoulder for receiving the heddle bar, and means for holding said heddle bar in position on said support, said means including a member mounted on the support for engagement with the heddle bar, a spring mounted on said support and 20 having a portion bearing against said member to urge it toward the heddle bar, and an adjustable member mounted on said support for movement to heddle bar locking position, one of said members being provided with a recess in which said spring 25 bears.

JOHN JACOB KAUFMANN.
